(57) **CLAIM**

The ornamental design for personal digital assistant, as shown and described.

DESCRIPTION

FIG. 1 is a front elevational view of a personal digital assistant showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front elevational view thereof, with a pen detached;

FIG. 8 is a top, front, right side perspective view thereof;

FIG. 9 is a top, front, right side perspective view thereof, with a cover attached;

FIG. 10 is a front elevational view of a second embodiment thereof;

FIG. 11 is a rear elevational view thereof;

FIG. 12 is a left side view thereof;

FIG. 13 is a right side view thereof;

FIG. 14 is a top plan view thereof;

FIG. 15 is a bottom plan view thereof;

FIG. 16 is a front elevational view thereof, with a pen detached;

FIG. 17 is a top, front, right side perspective view thereof;

FIG. 18 is a top, front, right side perspective view thereof, with a cover attached;

FIG. 19 is a front elevational view of a cover shown separately for clarity of illustration only;

FIG. 20 is a rear elevational view of the cover;

FIG. 21 is a right side view of the cover, the left side view being a mirror image;

FIG. 22 is a top plan view of the cover;

FIG. 23 is a bottom plan view of the cover; and,

FIG. 24 is a top, front, right side perspective view of the cover.
